US00D825497S

(12) **United States Design Patent** (10) **Patent No.:** **US D825,497 S**
(45) **Date of Patent:** **** Aug. 14, 2018**

(54) **INPUT DEVICE FOR INDUSTRIAL EQUIPMENT**

(71) Applicant: **Mitsubishi Electric Corporation**, Tokyo (JP)

(72) Inventors: **Yuki Mizushi**, Tokyo (JP); **Yoshinori Saigusa**, Tokyo (JP); **Koji Kiyohara**, Tokyo (JP); **Hongkue Lee**, Tokyo (JP)

(73) Assignee: **Mitsubishi Electric Corporation**, Tokyo (JP)

(**) Term: **15 Years**

(21) Appl. No.: **29/596,702**

(22) Filed: **Mar. 10, 2017**

(30) **Foreign Application Priority Data**

Sep. 12, 2016 (JP) 2016-019681
Sep. 12, 2016 (JP) 2016-019682

(51) LOC (11) Cl. **14-03**

(52) U.S. Cl.

USPC **D13/168**

(57) **CLAIM**

The ornamental design for an input device for industrial equipment, as shown and described.

DESCRIPTION

FIG. 1 is a front, top and right side perspective view of an input device for industrial equipment of an initial embodiment showing our new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a front, top and right side perspective view of an input device for industrial equipment of a second embodiment showing our new design;

FIG. 9 is a front view thereof;

FIG. 10 is a rear view thereof;

FIG. 11 is a top view thereof;

FIG. 12 is a bottom view thereof;

FIG. 13 is a left side view thereof; and,

FIG. 14 is a right side view thereof.

The parts shown in the broken lines do not form part of the claimed design.

1 Claim, 10 Drawing Sheets
